(57) **CLAIM**

The ornamental design for a lip product container, as shown and described.

DESCRIPTION

FIG. 1 is a perspective view of a lip product container in an open configuration showing my design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings showing the lip product container illustrate the portions of the lip product container that form no part of the claimed design.

The heavy shading (i.e., heavy stippling) in FIGS. 1-7 shows contrast in appearance relative to the lightly-shaded surface regions (i.e., light stippling) of the lip product container.
